UNITED STATES PATENT OFFICE.

WILLIAM D. FORSYTH, OF YOUNGSTOWN, OHIO, ASSIGNOR, BY MESNE ASSIGNMENTS,
TO RAILWAY PRODUCTS CORPORATION, OF BUFFALO, NEW YORK, A CORPORATION
OF NEW YORK.

METAL RAILWAY-TIE.

1,131,356.

Specification of Letters Patent.

Patented Mar. 9, 1915.

Application filed November 14, 1911. Serial No. 660,302.

To all whom it may concern:

Be it known that I, WILLIAM D. FORSYTH, a citizen of the United States, residing at Youngstown, in the county of Mahoning 5 and State of Ohio, have invented new and useful Improvements in Metal Railway Ties, of which the following is a specification.

This invention relates to metal railway 10 ties and more particularly to metal railway ties made from railroad rails which are no longer suitable for track purposes.

The principal object of this invention is to provide a new and useful metal railway tie 15 made from railroad rails no longer useful for track purposes.

The invention consists of metal railway ties formed from lengths or railroad tracks, together with means applied thereto of fastening the rails of the roadbed of a railroad 20 to said improved metal ties.

In the drawing forming part of the specification, Figure 1 is a plan view of my improved metal railway tie. Fig. 2 is a side elevation of Fig. 1. Fig. 3 is an end view of Fig. 2. Fig. 4 is an enlarged cross section of Fig. 2 on section line A—A. Fig. 5 is an enlarged perspective view of a wooden block insertible in the bent ends of the improved 30 tie. Fig. 6 is an enlarged end view of a rail saddle which is placed over the ends of the improved tie. Fig. 7 is a side view of Fig. 6.

Like figures of reference refer to like parts throughout.

The metal tie T shown in the accompanying drawing is made from a railroad rail 1. The end portions 5' of the rail 1 are bent back along opposite sides of the middle portion 5 of said rail to extend parallel to said 40 middle portion. The flanges of the end portions 5' and of the middle portion 5 of the rail 1 are in contact or close together. Upon the tie T near each end thereof is a rail saddle 2, which has a body portion 3 and two 45 downwardly extending flanges 4. The saddles 2 are slipped over the ends of the tie T; and when in position, the body portions 3 rest upon the heads of the portions of the rail 1 constituting the end portion 5' and the 50 adjacent part of the middle portion 5. The flanges 4 of the saddles 2 fit over and under the head of the rail 1 and hold the saddle in place. An integral lug 6 projects upwardly from the body portion 3 of each saddle 2

near each corner thereof; and these lugs 6 55 are spaced so as to receive the track rails 11 between them. A block 8 of wood or other similar fibrous material fits tightly within the space between the middle portion 5 and the corresponding end portion 5' of 60 the rail 1 near each end of the tie T. Each block 8 has a shoulder 9 which engages the under sides of the head of the rail 1 and holds the block in place. The saddle 2 has spaced holes 7 therein, through which ordinary spikes 12 are driven into the block 8 65 so as to hold the track rails 11 in position.

The saddles 2 are slidable upon the tie T and can be adjusted to give the proper gage to the track rails 11. While the end portions 5' of the tie are shown on opposite sides of the middle portion 5, said end portions 5' may be upon the same side of the middle portion without departing from the invention. 70

The construction shown and described may be considerably modified without departing from the invention, and I do not wish to be limited to the details of this construction. 75

What I claim as my invention is:

1. A metal railway tie comprising a piece of a railroad rail having both end portions thereof bent to extend parallel to the middle portion of said rail on opposite sides 85 thereof, a wooden block between each of said end portions and said middle portion of said rail, said blocks being adapted to receive and retain means for holding the track rails to said tie, and adjustable rail saddles having downwardly extending flanges fitting closely around the head of the rail in each of said end portions thereof and in said middle portion, said saddles each having upwardly extending lugs near the corners thereof 95 which are spaced to receive a track rail, said saddles having holes therein through which are driven the spikes for fastening the track rails to said tie. 95

2. A metal railway tie comprising a piece 100 of a railroad rail having both end portions thereof bent to extend parallel to the middle portion of said rail, a wooden block between each of said end portions and said middle portion of said rail, said blocks being adapted to receive and retain means for holding the track rails to said tie, and rail saddles adjustably mounted on said tie and 105

having downwardly extending flanges fitting closely around the head of said first-mentioned rail.

3. A metal railway tie comprising a piece 5 of a railroad rail having both end portions thereof bent to extend parallel to the middle portion of said rail, means inserted between each of said end portions and said middle portion of said rail for receiving and retaining rail fastening devices, and rail saddles

slidably mounted on said tie for supporting track rails.

In testimony whereof I have hereunto subscribed my name in the presence of two subscribing witnesses.

WILLIAM D. FORSYTH.
